BOWLING BALL ENGRAVING MACHINE

George Berlant, Bellerose, N.Y., assignor to New Hermes
Engraving Machine Corp., New York, N.Y., a corpora-
tion of New York

Filed Feb. 12, 1962, Ser. No. 68,771

Term of patent 14 years

(Cl. D64—11)

Fig. 1.

Fig. 2.

Fig. 5.

*Fig. 4.**Fig. 5.*

FIGURE 1 is a perspective view of a bowling ball engraving machine showing my new design;

FIGURE 2 is a top plan view thereof;

FIGURE 3 is a side elevation view thereof;

FIGURE 4 is an end elevation view thereof;

FIGURE 5 is a bottom plan view thereof.

I claim:

The ornamental design for a bowling ball engraving machine, substantially as shown.
